EMBOSSSED PLASTIC SHEET MATERIAL

Staley A. Carpenter, Marietta, Ohio, assignor to The
B. F. Goodrich Company, New York, N.Y., a corpora-
tion of New York

Filed June 13, 1960, Ser. No. 60,947

Term of patent 14 years

(Cl. D87—3)

Fig. 1

Fig. 2

Fig. 3

Figure 1 is a plan view of an embossed plastic sheet material, showing my new design;

Fig. 2 is an enlarged fragmentary plan view; and

Fig. 3 is a sectional view taken along the line 3-3 of Fig. 2.

I claim:

The ornamental design for an embossed plastic sheet material, substantially as shown.
